DESIGN FOR A TABLE

Lurelle Guild, New York, N. Y., and Carlton G. Towne, Pittsburgh, Pa., assignors to The Aluminum Cooking Utensil Company, New Kensington, Pa., a corporation of Pennsylvania

Application July 26, 1947, Serial No. 140,543

Term of patent 14 years

(Cl. D33—14)

To all whom it may concern:

Be it known that we, Lurelle Guild and Carlton G. Towne, citizens of the United States, residing, respectively, at New York, in the county of New York and State of New York, and at Pittsburgh, in the county of Allegheny and State of Pennsylvania, have invented a new, original, and ornamental Design for a Table, of which the following is a specification, reference being had to the accompanying drawing, forming a part thereof.

Fig. 1 is a view in perspective of a table embodying our new design;

Fig. 2 is a side elevation of the table of Fig. 1;

Fig. 3 is an end elevation of the table of Fig. 1;

Fig. 4 is an enlarged cross sectional view taken on the line 4—4 of Fig. 2; and

Fig. 5 is an enlarged cross sectional view taken on the line 5—5 of Fig. 3.

We claim:

The ornamental design for a table, substantially as shown.

LURELLE GUILD.
CARLTON G. TOWNE.
